UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 30,355, dated March 14, 1899.

Application filed February 2, 1899. Serial No. 704,300. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing, making a part of the same.

The leading feature of my design consists in a woven fabric which comprises the representation of a central ornamental diamond-shaped panel, as shown, the whole surrounded

by an ornamental border, as shown in the drawing.

Having as above fully described my design, what I claim as new, and desire to secure by Letters Patent, is—

The design for a woven fabric as shown in the accompanying drawing and described in the specification.

W. T. SMITH.
